LUG WRENCH BRACE

John H. Cline and Jackie D. Cline, both of
R.R. 2, Wakeeney, Kans.

Filed Apr. 15, 1965, Ser. No. 84,795

Term of patent 14 years

(Cl. D54—13)

FIG. 1.

FIG. 2.

FIGURE 1 is a perspective view looking down and to the right upon the lug wrench brace, showing our new design; and

FIGURE 2 is a front elevation thereof.

The rear elevation is identical to the front elevation and the bottom is plain.

We claim:

The ornamental design for a lug wrench brace, as shown and described.
